(57) **CLAIM**

The ornamental design for outlet shelf as shown and described.

DESCRIPTION

FIG. 1 is a front perspective view of the outlet shelf according to the invention;

FIG. 2 is a front elevation view of the outlet shelf depicted in FIG. 1;

FIG. 3 is a right elevation view of the outlet shelf depicted in FIG. 1;

FIG. 4 is a left elevation view of the outlet shelf depicted in FIG. 1;

FIG. 5 is a top plan view of the outlet shelf depicted in FIG. 1; and,

FIG. 6 is a bottom plan view of the outlet shelf depicted in FIG. 1.

The broken lines shown in the drawings represent portions of the outlet shelf that form no part of the claimed design.

1 Claim, 6 Drawing Sheets
